UNITED STATES PATENT OFFICE.

WILLIAM M. MITCHELL, OF LOUISVILLE, KENTUCKY.

RAIL-ANCHOR.

1,264,959.

Specification of Letters Patent. Patented May 7, 1918.

Application filed February 14, 1918. Serial No. 217,176.

To all whom it may concern:

Be it known that I, WILLIAM M. MITCHELL, a citizen of the United States, residing at Louisville, in the county of Jefferson and State of Kentucky, have invented certain new and useful Improvements in Rail-Anchors, of which I do declare the following to be a full, clear, and exact description, reference being had to the accompanying drawings, forming a part of this specification.

The present invention has relation more particularly to rail anchors of that type in which the anchor or a member thereof is connected with the railway rail by a fused or welded joint. Examples of this type of rail anchor are shown in various Letters Patent granted to me under date of July 31, 1917, and October 23, 1917. The present invention consists in the features of novelty hereinafter described, illustrated in the accompanying drawings and particularly pointed out in the claims at the end of this specification.

Figure 1 is a view in side elevation showing a part of a railway rail and several of the railway track ties with my invention applied thereto. Fig. 2 is a plan view of the part shown in Fig. 1. Fig. 3 is a view in vertical cross section centrally through the fused or welded stud. Fig. 4 is a perspective view of a portion of a railway rail showing a modified form of the invention applied thereto. Fig. 5 is a plan view similar to Fig. 1 but showing a modified form of the invention. Fig. 6 is a plan view showing a further modification of the invention. Fig. 7 is a perspective view showing a modification of the invention.

A designates a railway rail having the usual base flanges *a* and *B* denotes the cross ties of the track upon which the rail *A* rests, the rail being held to the ties by spikes *b* in the usual manner.

Referring more particularly to the embodiment of the invention shown in Figs. 1, 2 and 3 of the drawings, *C* designates a lug or bar that is fused or welded to one of the base flanges *a* of the rail *A*. As shown, the inner end of the lug or bar *C* is formed with a shoulder *c* adapted to abut against the edge of the base flange *a* of the rail and with a flange *c'* adapted to overlap the top of the base flange *a* of the rail, the fused or welded joint between the lug or bar *C* and the base flange of the rail *a* occurring

where the shoulder *c* and the flange *c'* meet the base flange *a* of the rail. In the lug or bar *C* is formed a hole *c*² through which passes a bolt *D* or similar connecting device adapted to connect the lug or bar *C* with the tie-engaging bar or member *E* that is preferably united, as by spikes *e*, to a plurality of cross ties *B* of the track. The bolt *D* is shown as furnished at one end with a head *d* and at its opposite end with a nut *d'*. The bar *E* is preferably formed with a bent or offset portion *e'* where it laps the outer portion of the lug or bar *C*.

In the modified form of the invention illustrated in Fig. 4 of the drawings, a lug or bar *C'* is shown as fused or welded at *c'* to the edge of the base flange *a* of the rail *A* and in this form of the invention, the lug or bar *C'* has its outer end bifurcated or formed as a yoke to receive the longitudinal bar *E'* which parallels the base flange *a* of the rail *A*. The bolt *D* is shown as passing through the bar *E'* and through the jaws of the lug or bar *C'* to securely hold these parts together. With this form of my invention, the central portion of the longitudinal bar *E'* need not be bent or offset.

In the modified form of the invention illustrated in Fig. 5 of the drawing, the lug or bar designated as *C*² that is welded to the base flange *a* of the rail is shown as formed integral with the longitudinal bar or tie-engaging bar *E*² that is spiked to the ties *B*.

In the modified form of the invention shown in Fig. 6, the longitudinal bar or tie-engaging member *E*³ is shown as formed with an inwardly bent or offset portion *e*³ that forms in effect the lug or projection that is connected to the edge of the base flange *a* of the rail *A* by a fused or welded joint *e*⁴. In this form of the invention, as in that illustrated in Figs. 4 and 5, the longitudinal or tie-engaging bar *E*³ is directly opposite and in the plane of the base flange *a* of the rail *A*.

In Fig. 7, I have shown the base flange *a* of the rail *A* as provided with a slotted lug or bar *C*⁴, the inner end of which is fused or welded to the edge of the rail, as shown in Patent No. 1,244,356, granted to me October 23, 1917. Across this lug or bar *C*⁴ extends the longitudinal or tie-engaging bar *E*⁴ that is provided with a hole *e*⁴ to receive a spike, wood screw or bolt, (not shown) that will be passed through

the slot of the lug c^4 and through the hole e^4 of the bar E^4 and into the track tie B. The ends of the bar E^4 may be extended any desired distance to pass over 5 other cross ties and this bar will be provided with suitable holes to receive spikes for attachment of the bar E^4 to the cross ties. The central portion of the bar E^4 is slightly offset to enable it to pass across 10 the lug or bar C ^{4} . I prefer that the tie-engaging bar or member that will be spiked to the ties shall be formed as a flat bar and that the central portion of the bar that will be connected with the base flange of 15 the rail shall be flat, as by such construction of bar a bending of the central portion of the tie-engaging bar at right angles to the end portions of the bar, as in my Patent No. 1,235,495, dated July 31, 1917, 20 is avoided.

Having thus described my invention, what I claim as new and desire to secure by Letters Patent is:—

1. The combination with a railway rail, 25 of a tie-engaging bar extending at one side of a base flange of the rail and having a flat longitudinally disposed central portion at one side of the base flange of the rail and connected thereto by a part or member fused or welded to said base flange.

2. A rail anchor comprising a stud or flange fused or welded to the base flange of

the rail at its edge, and a tie-engaging bar having its ends extending parallel with and in the plane of the base flange of the rail at 35 one side thereof, the central portion of said tie-engaging bar extending horizontally and across said stud or projection and connected thereto.

3. A rail anchor comprising a stud or 40 projection fused or welded to the base flange of the rail, and a tie-engaging bar arranged at one side of the base flange of the rail and extending parallel therewith and in the plane of said base flange substantially 45 from end to end, said bar being connected to said stud or projection.

4. A rail anchor comprising a stud or projection fused or welded to the base flange 50 of the rail at its edge, and a tie-engaging bar arranged at one side of the base flange of the rail and extending across said stud or projection and detachably connected thereto.

5. A rail anchor comprising a stud or projection fused or welded to the base flange 55 of the rail at its edge, and a tie-engaging bar arranged at one side of the base flange of the rail and having a horizontal central portion extending across said stud or projection and detachably connected thereto, one of said parts being arranged out of the plane of the base flange of the rail where it crosses the other of said parts. 60

WILLIAM M. MITCHELL.
